W. J. MILLS

BATHTUB JACK

Filed May 21, 1923

FIG. 1.

FIG. 2.

FIG. 3.

FIG. 4.

Inventor

W. J. Mills

Witness

George M. Knauth

By *H. Blodgeson* Attorney

UNITED STATES PATENT OFFICE.

WILLIAM JAMES MILLS, OF WEST HAZLETON, PENNSYLVANIA.

BATHTUB JACK.

Application filed May 21, 1923. Serial No. 640,511.

To all whom it may concern:

Be it known that I, WILLIAM JAMES MILLS, a citizen of the United States, residing at West Hazleton, in the county of Luzerne and State of Pennsylvania, have invented certain new and useful Improvements in Bathtub Jacks; and I do declare the following to be a full, clear, and exact description of the invention, such as will enable others skilled in the art to which it appertains to make and use the same.

My invention has for its principal object to provide an extremely simple and inexpensive, yet a highly efficient and desirable jack for lifting bath tubs or other articles while inserting linoleum or other floor coverings thereunder.

In carrying out the above end, I provide an adjustable screw-threaded rod which carries the head of the jack, and a further object is to connect said head and rod in a simple manner which will hold them against relative rotation.

With the foregoing in view, the invention resides in the novel subject matter herein-after described and claimed, the description being supplemented by the accompanying drawing.

Figure 1 is an elevation showing the use of the jack for lifting one end of a bath-tub.

Figures 2 and 3 are elevations of the jack looking in different directions.

Figure 4 is a central longitudinal sectional view.

Figure 5 is a transverse section on line 5—5 of Fig. 2.

In the drawing above briefly described, which illustrates the preferred form of my invention, the numeral 1 designates a vertically disposed shank which may well be formed of wood, the lower end of said shank having a ferrule 2 which carries a vertically disposed plate 3 adapted to rest in the angle between the floor and wall of a room, as shown in Fig. 1. The plate 3 is preferably offset to some extent from the shank 1 and may well be provided on its lower edge with teeth 4 which prevent slipping under circumstances which might otherwise permit such slipping.

The upper end of the shank 1 is provided with a longitudinal bore 5 which opens through its upper extremity and the latter is preferably reinforced by a metal cap 6 having an opening registering with said bore. A screw-threaded rod 7 passes

through the opening in the cap and is slidably received in the bore 5, being provided with an appropriate wing-nut 8 normally contacting with said cap. The upper end 60 of the rod 7 carries a horizontally elongated rectangular head 9 which is shaped to fit under the rim of a bath tub as shown in Fig. 1, and a simple yet efficient connection is provided between the rod and head to 65 hold the latter against turning when rotating the nut 8 to raise the tub.

In the preferred form of construction, the head 9 is formed of a main lower section 10 and a supplemental upper section 11, both 70 of which may well be formed of wood and secured together by ordinary wood screws 12. The inner or upper side of the head section 10 is provided with a flat sided socket 13 and said section is formed with 75 a central opening 14 leading from said socket to the lower side of the head. The rod 7 is received in this opening and is provided with a flat-sided head 15 snugly received in the socket 13 and held in the latter 80 by the head section 11. This construction is simple and inexpensive, yet will produce the desired result.

From the foregoing taken in connection with the accompanying drawing, it will be 85 seen that I have provided an extremely simple and inexpensive jack which may be advantageously used for raising bath tubs while inserting floor coverings thereunder. Also, the device may be used for other purposes if desired and in all instances will be 90 highly efficient.

As excellent results may be obtained from the details disclosed, they are preferably followed, but within the scope of the invention as claimed, minor changes may be made.

I claim:

1. A bath tub jack for use in laying floor coverings, comprising an upright shank having a flat vertically disposed plate at its 100 lower end adapted to rest in the angle between a floor and wall, the upper end of said shank having a vertical bore, a threaded rod received slidably in said bore and extending above said shank, a wing nut 105 threaded on said rod and engaging the upper end of said shank, and a head secured to the upper end of said rod, said head being horizontally elongated and shaped to fit under the rim of a bath tub.

2. A jack comprising a shank having in one end a longitudinal bore, a ferrule on

the opposite end of said shank and having on its outer end a flat plate, a cap on the bored end of said shank, and having there-in an aperture in line with the bore of the shank, a threaded rod adjustable in said bore, an adjusting nut threaded on said rod and coacting with the cap on said shank and

a head secured on the outer end of said threaded rod to permit said end of the rod to turn therein.

In testimony whereof I have hereunto affixed my signature.

WILLIAM JAMES MILLS.
